UNITED STATES PATENT OFFICE.

MELVILLE EASTHAM, OF BOSTON, MASSACHUSETTS, ASSIGNEE TO CLAPP-EASTHAM COMPANY, OF BOSTON, MASSACHUSETTS, A CORPORATION OF MASSACHUSETTS.

TRANSFORMER.

965,168.

Specification of Letters Patent. Patented July 26, 1910.

Application filed September 3, 1909. Serial No. 516,097.

To all whom it may concern:

Be it known that I, MELVILLE EASTHAM, a citizen of the United States, and resident of Boston, in the county of Suffolk and State of Massachusetts, have invented new and useful Improvements in Transformers, of which the following is a specification.

My invention relates to apparatus for charging condensers and is peculiarly applicable to circuits employed in wireless telegraphy, wherein a transformer is used to charge a condenser.

The objects of my invention are; to prevent the formation of an arc at the spark gap in such circuits, to cause a decrease of current in the primary of the transformer when the secondary is short circuited by the operation of the spark gap, to dispense with control resistance or inductance and to enable the primary of the transformer to be tapped at any number of different points so as to vary the power of the instrument, to reduce both primary and secondary resistance to lower quantities than are common in most types of transformers, and to secure a high power factor by offsetting the leading current due to the condenser capacity by the lagging current due to the inductance of the transformer secondary.

In the drawings hereto annexed which show in diagrammatic form an example of my invention, A and D are the primary and secondary respectively of a closed core transformer, the core of which is represented by B. The primary A may be tapped from various points in its winding. The magnetic leakage of the closed core transformer is large; this large leakage is secured by the intermediate core spur C which is joined to or preferably integral with the core B at one side and is separated from the other side of the core by a very thin air gap at E.

The resonant circuit of which the secondary D is a component part contains the condenser H in series with the secondary coil and the spark gap F in shunt across the condenser. This spark gap for purposes hereinafter to be set forth is preferably adjustable. The secondary D is constructed so that its inductive reactance closely approximates to the capacity reactance of the condenser H for whatever alternating current frequency may be adopted or employed; this approximation of reactance allows a large current to flow into the condenser when

charging for the reason that the inductance of the secondary is neutralized by the capacity of the condenser. When however, the condenser is discharged at the spark gap F, the previously existing resonant condition of the circuit is destroyed by the formation of the spark, and the full inductance of the secondary being thus brought into play, the current is lowered to such an extent that it will not maintain an arc at the spark gap F.

When the secondary is open circuited the lines of force from the primary A follow the closed magnetic circuit B but when the secondary is short circuited by the operation of the spark gap F, the opposing magnetic field caused by the current in the secondary obliges most of the lines of force from the primary A to complete themselves through the magnetic-leakage tongue C, crossing the air gap E.

By means of the above described arrangement the formation of an arc at the spark gap is prevented, the current in the primary is decreased whenever the secondary is short circuited, the transformer does not require the use of a controlling resistance or inductance as the primary may be tapped at any one of several points thus allowing the operator to choose between several available amounts of power. Moreover the resistance of the primary and secondary may be made much lower than usual by reason of the current control by reaction between the several members of the transformer. If desired, a spark frequency lower than that of the supply current may be obtained by opening the adjustable spark gap F so far that several successive cycles are required to accumulate the energy needed to charge the condenser H to the sparking potential. It will be obvious also that the power factor of the transformer is high because the leading current due to the capacity of the condenser is neutralized by the lagging current caused by the inductance of the transformer secondary, since the capacity reactance of the one is equal or approximately so to the inductive reactance of the other.

What I claim and desire to secure by Letters Patent is:—

1. A resonant circuit comprising the secondary of a closed core transformer characterized by large magnetic leakage, a condenser in circuit with the said secondary, the secondary having an inductive reactance

approximately equal to the capacity reactance of the condenser for the alternation-frequency of the supply current.

2. A resonant circuit comprising the secondary of a closed-core transformer which has a nearly closed magnetic shunt, a condenser in circuit with said secondary, the secondary having an inductive reactance approximately equal to the capacity reactance of the condenser for the alternation-frequency of the supply current.

3. The combination of a closed core transformer having large magnetic leakage, a condenser in series with the secondary, the secondary having an inductive reactance approximately equal to the capacity reactance of the condenser for the alternation-fre-

quency of the supply current, and an adjustable spark gap, in shunt across the condenser.

4. The combination of a core transformer having large magnetic leakage, a condenser in series with the secondary, the secondary having an inductive reactance approximately equal to the capacity reactance of the condenser for the alternation-frequency of the supply current, and a spark-gap in shunt across the condenser.

Signed by me at Boston, Massachusetts this fourteenth day of August 1909.

MELVILLE EASTHAM.
